DISHWASHING MACHINE

Original Filed May 21, 1923 3 Sheets-Sheet 3

UNITED STATES PATENT OFFICE.

JAMES BARRY, OF GRAFTON, CALIFORNIA.

DISHWASHING MACHINE.

Application filed May 21, 1923, Serial No. 649,337. Renewed November 23, 1927.

This invention relates to means for cleansing and sterilizing dishes and culinary utensils.

It is the principal object of the present invention to provide a machine for mechanically cleansing and sterilizing dishes and the like, which embodies the use of an improved operating structure of simple construction, which structure acts to rapidly and thoroughly cleanse dishes and other like utensils as they are continuously fed through the machine.

In carrying out this object I provide a plurality of tanks divided into independent and successive compartments into which dishes may be delivered. The tanks mentioned are designed to receive different types of dishes and each is equipped with mechanisms for continuously moving the dishes through the successive compartments and to thoroughly cleanse and sterilize them during their travel.

One form which the invention may assume is exemplified in the following description and illustrated by way of example in the accompanying drawings, in which:

Fig. 1 is a plan view of a machine embodying the preferred form of my invention.

Fig. 2 is a longitudinal section through the same taken on line 2--2 of Fig. 1.

Fig. 3 is a side elevation of the drive side of the machine.

Referring more particularly to the accompanying drawings, 10 indicates a rectangular housing which longitudinally divided into a plurality of independent tanks by partition walls 11. These tanks are preferably formed of different widths to accommodate various types of dishes, bowls, cups and other like utensils. The tanks are each divided transversely by partition walls 12 into independent and successive compartments as shown in Fig. 1. The tanks in the present instance each comprise an equal number of compartments. However, it is understood that any number of tanks and compartments may be employed and also that the machine may be designed to operate on culinary utensils other than the articles previously mentioned.

The feed end of the machine is fitted with an inclined shelf 14 to which articles to be washed are delivered. This shelf is partitioned by continuations of the longitudinal partition walls of the tanks and is positioned adjacent an entry opening 15 in the end wall

16 of the housing. This opening communicates with the first compartment 17 of each tank. The compartments of the tanks are fitted with inclined false floors 18 which are preferably constructed of foraminous material. These floors are arranged in parallelism and are cut away adjacent their lower ends to accommodate lower rotary brushes 19. It is intended that dishes delivered to the compartments 17 be lowered into the tank by gravity along the false floors 18 therein.

To keep dishes fed to the machine continuously moving therethrough, conveyor mechanisms 20 are provided and are positioned intermediate the lower ends of the false floors 18 of the compartments and the upper end of the false floors of the adjacent compartments. These conveyors are fitted with lugs 21 and are disposed on an incline opposite that of the false floor members. The conveyors are designed to operate to elevate dishes lowered to the bottom of the compartments and deliver them to the next compartment. In this manner dishes fed to the delivery shelf 14 are continuously conveyed through the compartments. The dishes are elevated from the last compartment by a conveyor 22 and delivered to an inclined drying tray 23 located at the discharge end of the machine.

The first two compartments of each tank are fitted with upper rotary brushes 24 which are disposed above the false floors 18. It is intended that the upper and lower brushes 19 and 24 co-operate to wash the surfaces of dishes fed to the machine.

Two of the tanks, those indicated at 25 and 26, are of a width to accommodate bowls, cups and the like and the brushes 24 therein, in the first compartment, are connected with their drive shaft by a universal joint 25^a. It will be noticed that the transverse shaft which drives the brushes 24 is formed of two parts which project inwardly from opposite sides of the tank. One of these parts, indicated by the numeral 24^a, extends through the outer partition of the compartment 26 a slight distance and is connected to the core of the brush by the universal joint 25^a. This universal joint may be of any standard construction, permitting the free end of the brush to be forced downwardly as will be described. The connection between the other brush 24 and the other part of the shaft 24^a is exactly

the same. This construction permits them to be projected into the interior of a bowl or cup to wash the same. For this purpose the brushes are connected by links 27 to pivoted levers 28 located at the top of the housing. By referring to Fig. 2 it is obvious that the levers may be manipulated to insert the brushes into cups or bowls disposed therebeneath.

10 The compartments of the tanks are each fitted with a valve controlled inlet pipe 30 which connects with a suitable source of water supply. The compartments are also fitted with valve controlled drain pipes 31 which connect with a common outlet pipe so that the water in the tanks may be changed as desired.

20 Gas burners 32 are mounted below the tanks for the purpose of maintaining the water therein at a high temperature. A gas burner 33 is also disposed below the drying tray and may be employed to dry the dishes after they have passed through the tanks. It is understood that other means 25 may be employed to heat the water in the tanks and dry the washed dishes.

For continuously driving the conveyers and the brushes, I provide a drive shaft 34 fitted with a pulley 35 which may be connected by a belt to a pulley of a driving motor. The drive shaft is also fitted with a pulley 36 connected by a belt to a pulley 37 on a shaft of conveyers 20 in the first compartment. This shaft is connected by 30 sprocket and chain mechanism 39 to the lower shafts 40 of the other conveyors 20. These shafts are connected by spur gears 41 to the shafts of the rotary brushes 19. The upper shafts 42 of the conveyors in the 40 first two compartments are connected by sprocket and chain mechanisms to the shafts of the rotary brushes 24. It is obvious that when the drive shaft is driven that the conveyors will operate continuously in the same 45 direction and that the rotary brushes will be revolved.

In operation, tanks are filled with water from the inlet pipes 30 and the gas burners are started to heat the water to a high temperature. A cleansing solution may be placed in the first two compartments of the tanks but it is preferred that the last compartment contain clear water.

50 Dishes or other similar articles to be washed may then be fed to the delivery shelf 14 and will lower by gravity downwardly into the tanks along the false floors 18 and between the brushes 19 and 24. In the case that cups and bowls are being 55 washed, the levers 28 may be manipulated to project the brushes 24 in the tanks 25 and 26 into the cups or bowls to wash them.

When the dishes reach the bottom of the first compartments the lugs on the conveyors 60 20 engage them and elevate them to the

false floors of the succeeding compartments wherein they undergo a second washing.

By the time dishes reach the last compartment they are thoroughly washed and the clear water in the last compartment 70 acts to rinse and sterilize them.

It is seen that by the provision of the separate inlet and drain pipes, the compartments of the tanks may be cleaned and drained as often as desired.

75 From the foregoing it is obvious that a very desirable machine has been provided which may be efficiently operated to thoroughly wash and sterilize dishes and like articles.

80 While I have shown the preferred form of my invention, I wish it understood that various changes in the construction and arrangement of the various parts of my device may be made without departing from the invention as defined in the appended claims.

85 Having thus described my invention, what I claim and desire to secure by Letters Patent is:—

90 1. A dish washing machine comprising a housing divided transversely into three independent compartments, separate fluid inlet and discharge connections for each of said compartments, said housing being formed with an entry opening at one end and an exit opening at the other end, a foraminous inclined floor member in each compartment, said floors being disposed in parallelism, and each having an opening therein adjacent its lower end, transversely disposed lower rotary brushes disposed one beneath the floor member in each compartment and projecting partly through the opening therein to engage dishes passing over said floor, upper rotary brushes disposed one in each of the 95 first two compartments, said brushes being disposed above the floor members whereby dishes passing over the floor members will pass between the upper and lower brushes and be engaged thereby, an inclined conveyor in each compartment, said conveyor being inclined oppositely to the floor member so as to be disposed between the lower end of the floor member in the compartment and the upper end of the floor member of the 100 succeeding compartment whereby dishes fed into the first compartment will pass downwardly over the floor member between the brushes and then be elevated by the conveyor 105 and deposited upon the top of the floor member of the succeeding compartment.

110 2. A dish washing machine comprising a housing divided transversely into three independent compartments, separate fluid inlet and discharge connections for each of said compartments, said housing being formed with an entry opening at one end and an exit opening at the other end, a foraminous inclined floor member in each compartment, 115 said floors being disposed in parallelism,

and each having an opening therein adjacent its lower end, transversely disposed lower rotary brushes disposed one beneath the floor member in each compartment and projecting 5 partly through the opening therein to engage dishes passing over said floor, a brush drive shaft extending transversely into the first compartment above the foraminous floor therein, a brush connected with said 10 shaft by a universal connection, a vertical reciprocable rod connected with said brush whereby the brush may be projected into the interior of a bowl or cup passing over the foraminous floor of the first compartment, 15 and a pivoted lever at the top of the housing

for operating said reciprocable rod, a brush drive shaft extending transversely through the second compartment, a rotary brush mounted thereon above the foraminous floor whereby dishes passing over the floor member 20 will pass between the upper and lower brushes therein, an inclined conveyor in each compartment, said conveyor being inclined oppositely to the floor member so as to be disposed between the lower end of the floor member in the compartment and the upper 25 end of the floor member of the succeeding compartment.

JAMES BARRY.
